HEATING, DRYING, AND AIR CONDITIONING
APPARATUS

Earl B. Hough, Detroit, Mich.

Application August 18, 1943, Serial No. 499,304

5 Claims. (CL 34—87)

This invention relates to heating, drying, and air conditioning apparatus, and has particular reference to a cabinet unit which includes a drying apparatus for laundry or dry cleaning, an air heating and circulating apparatus, and a water heater, together with suitable controls therefor.

Principal objects of the invention are:

To provide a combination unit which is constructed and arranged so as to circulate and/or heat air, to dry or process laundry or dry cleaning, and to heat water;

To provide a compact, simple and efficient unit for performing the several functions herein referred to;

To provide a combination laundry drier and air heater with means for selectively controlling the operation thereof; and

To provide a laundry drier with means by which the same may be used for processing laundry or other material in an atmosphere of steam or other vapor for sanitation purposes.

Other objects and advantages of the invention will be apparent from a consideration of the following specification, taken in conjunction with the accompanying drawings, of which there are two sheets and wherein:

Fig. 1 is a front elevational view of a device embodying the invention, with parts broken away and others illustrated in section in order to show the construction and operation of the device; and

Fig. 2 is a vertical cross sectional view taken along the staggered line 2—2 of Fig. 1, looking in the direction of the arrows.

As illustrated in the embodiment of the invention selected for purposes of illustration, the device comprises in general a cabinet 10 forming a housing and support for a rotary drier or tumbler drum 12, an air circulating unit 14, a heat generating and heat exchange device 16, and a water heater 18.

The cabinet, as illustrated, may be rectangular in cross section, having front and rear walls 20 and 22, side walls 24 and 26, top wall 28, and bottom wall 30 constructed in any suitable fashion. The interior of the cabinet is divided by suitable partitions into a compartment 32 in which a rotary drier 12 is arranged, a compartment 34 in which the air circulating unit is arranged, and a compartment 36 in which the heat generating and heat exchange device is arranged.

The compartment 32, as illustrated, is cylindrical in form and is defined by circular wall 38, front wall 40, and rear wall 42. An opening 44 at the upper end of the compartment 32 provides a discharge outlet therefrom, while an opening

46 in the cylindrical wall at the lower end of the compartment provides an inlet therefor. Within the compartment 32 a rotary drier 48 is arranged for rotation on a horizontal axis. The rotary drier 48 includes a foraminated cylindrical wall through which air can freely circulate, and front and rear walls 50 and 52. Rear wall 52 is provided with a spindle 54 journaled in bearing 56 which is carried by the rear wall 42 of the compartment, while front wall 50 is provided with a neck 58, the outer surface of which is supported by roller bearings 60 suitably carried by the front wall 48 of the compartment.

The bearings 60 and neck 58 rotatably support the front end of the rotary drier 48, while the spindle 54 and bearing 56 rotatably support the rear end of the rotary drier. The neck 58 extends through a suitable opening formed in the wall 48 and provides for access to the interior of the rotary drier 48 in order to insert and remove material therefrom. This access opening is adapted to be closed by a cover 62 hinged at 64 to the front wall 20 of the cabinet, and a suitable lock 66 is provided for securing the cover 62 in closed position.

A suitable running seal (not shown) may be provided between the outside of the neck 58 and the opening in the wall 48 through which it extends so as to prevent the escape of air or other vapors from the compartment 32 into the space enclosed by the outer shell of the cabinet.

The inside of the circular wall of the drier 48 may be provided with a plurality of axially extending baffles 68 spaced from each other so as to cause the laundry or other material which is arranged in the drier 48 for processing to be tumbled upon rotation of the drier.

The spindle 54 projects beyond the bearing 56 and has a pulley 70 affixed thereto for rotation therewith. Pulley 70 is adapted to be driven by a belt 72 which in turn is driven by a pulley 74 mounted upon a shaft 76. The shaft 76 is an idler shaft which is carried by an arm 78 suitably supported through a pin and slot connection 80, and a spring 82 is connected to the arm 78 in such a manner as to tension the belt 72 and position the pulley 74. Another pulley 84 is arranged on the shaft 76 for rotation with the pulley 74, and this pulley 84 is driven by a belt 86 which in turn is driven by a pulley 88 which is journaled on the shaft 90 of motor 92.

A clutch 94 is arranged between the shaft 90 and the pulley 88, and this clutch may comprise a dog clutch member 96 which is slidably splined on the shaft 90 and which has axially extending

clutch teeth cooperable with complementarily formed clutch teeth on the pulley 88 for driving the same. The clutch 84, as illustrated in Fig. 2, is engaged and is adapted to be disengaged by a fork 88 which runs in a groove in the clutch member 86 and which is adapted to shift the same to the right so as to disengage the teeth of the clutch 84 in order to break the driving connection between the motor 82 and the drier 48.

The fork 88 comprises a bellcrank which is pivoted at 100, the other arm of the bellcrank being connected to one end of a link 102 the other end of which is connected to an arm 104 of a rock or control shaft 106, the shaft 106 having a handle 108 at the front of the cabinet by means of which the mechanism just described may be operated so as to engage or disengage the clutch 84.

The handle 108 is provided with a pawl 110 which is selectively engageable with notches 112 and 114 formed in a quadrant 116 for positioning the handle in either of its two positions.

The air circulating unit 14 comprises a blower 120, the fan or rotor of which may be directly connected with the shaft of the motor 82 so as to be driven thereby. The blower 120 is arranged in the compartment 34 and has its intake 122 arranged to draw in air from the compartment 34. The compartment 34 is formed between the inside wall of the cabinet 10 and the outside wall of the drier compartment 32 and is provided with inlet openings 124 in which filters 126 are arranged for filtering the air prior to its entry into the compartment 34. The filters 126 may be removably arranged in the inlet openings 124 which may be formed in the rear wall of the cabinet 10.

The discharge outlet 128 of the blower 120 is arranged so as to deliver air into the compartment 36. The compartment 36 is arranged below the compartment 32 and defined by a generally horizontally extending wall 130 which extends between the walls 40 and 42, and a generally vertically extending wall 134 depending from the wall 130 and closing the space therebelow and between the walls 40 and 42. The blower discharge 128 is aligned with a suitable opening in the wall 134. The other side wall of the compartment 36 is formed by a part of the side wall 26 of the cabinet, and such part of the side wall 26, as well as the vertical wall 134, may have heat insulation 136 affixed thereto.

The heat generating and heat exchange device 18 may comprise a combustion chamber 138 in which a fuel burning means 140 is arranged. The walls of the combustion chamber 138 are defined by a metallic shell 142 having flue outlet 144 connected to a pipe 146 which leads to a suitable vent. While the fuel burning means, as illustrated, may comprise a gas burner which is adapted to be supplied with fuel under the control of a valve 148, any desirable or suitable form of fuel burning means and control therefor may be employed. Operation of the burner 140 will generate heated products of combustion, thereby heating the shell 142 which functions as a heat exchanger and which is exposed to the air which is circulated through the compartment 36 by the blower 120. Water heating coil 18 may be arranged in the combustion chamber 138 for heating water, and this water heater 18 may be connected in any conventional manner to the water system of the building or dwelling in which the device is arranged.

The compartment 36 is provided with two outlets, one formed by the inlet 46 to the drier compartment 32, and the other 154 which communi-

cates with a duct 156 for conducting heated air to space externally of and remote from the cabinet for heating the same. The outlets 46 and 154 from the compartment 36 are controlled by a valve or damper 158 which is carried by the rock shaft 106 for movement therewith.

In the position in which the parts are illustrated in Fig. 1, the valve 158 is closing the outlet 154, thereby directing the air discharged by the blower 120 into the drier compartment 32. The position of the valve 158 is controlled by the handle 108 which also controls the clutch 84 so that if the motor 82 is operating, the blower 120 is circulating air through the compartment 36 and through the drier compartment 32, and through the discharge 44 therefrom, while at the same time the driving connection between the motor 82 and the drier 12 is rotating the same.

Shifting of the handle 108 to the position in which the pawl 110 will engage the notch 114 will disengage the clutch 84 as well as shift the valve 158 to close the opening 46, thereby permitting the air which circulates through the compartment 36 to pass to the duct 156 for distribution to the space to be heated. The air discharged by the blower 120 in passing through the compartment 36 will absorb heat from the heat exchanger 142, and in passing through the compartment 32 will function to absorb moisture from the laundry or other material which is being tumbled in the drier 12.

The outlet 44 from the chamber 32 may be connected by a pipe 160 to a suitable vent, and a manually controlled damper 162 may be arranged in the outlet 44 for controlling the discharge of air from the compartment 32. By positioning the damper 162 in closed or partially closed position, discharge of air and vapor may be so restricted as to generate a relatively high temperature in the compartment 32 so as to generate an atmosphere of steam or other vapor for the purpose of processing the material arranged in the drier 12.

While the invention has been described with some detail, it is to be understood that the description is for the purpose of illustration only and is not definitive of the limits of the inventive idea. The right is reserved to make such changes in the details of construction and arrangement of parts as will fall within the purview of the attached claims.

I claim:

1. In a device of the character described, a cabinet having a chamber and an air passageway therein, the wall of the cabinet having an air inlet for the admission of outside air into one end of said air passageway, a blower having its inlet communicating with said passageway, a motor for actuating the blower, a rotary drier located within said chamber, a driving connection between said drier and said motor for actuating said drier during operation of said motor, a heat exchange device arranged in the path of air discharged by said blower, said chamber having an inlet connected with the discharge side of said blower, said passageway having an outlet for discharging heated air externally of said cabinet, a damper for selectively controlling the passage of air into said chamber through the inlet thereof or through said outlet, and common control means for shifting said damper to close said inlet and for breaking said driving connection, said chamber being provided with an air outlet therefrom.
2. In a device of the character described, a cabinet having an air passage and a chamber there-

in, said chamber being provided with an air outlet therefrom, the wall of the cabinet having an air inlet for the admission of outside air into one end of said air passage, a blower having its inlet communicating with said air passage, a motor for actuating the blower, a rotary drier located within said chamber and adapted to be actuated by said motor, a heating chamber connected with the discharge side of the blower so as to receive air discharged therefrom, a damper controlled opening between said chambers for controlling the passage of heated air from said heating chamber into said other chamber, a driving connection including a clutch between said motor and drier for driving the latter, said clutch being controlled coincidentally with said damper controlled opening so that said drier is arranged to be driven by said motor when said damper controlled opening is open, said heating chamber being provided with another opening through which air is discharged externally of said cabinet when said damper controlled opening is closed, and means for preventing the driving of said drier by said motor when said damper controlled opening is closed.

3. In a device of the character described, a cabinet, a chamber therein, a clothes tumbler in said chamber, said chamber being provided with an air inlet and a vent, a heat exchange device, an air passageway through said cabinet having an inlet communicating with the exterior thereof and an outlet for discharging air therefrom, a heater in said passageway for heating air as it circulates therethrough, a blower for circulating air through said passageway, said chamber inlet communicating with said passageway on the downstream side of said heater, a motor connected with said blower and said tumbler for actuating the same, damper means for selectively closing said chamber inlet or said outlet of said passageway, a control for said damper means, and means actuated by the positioning of said damper means to close said chamber inlet for preventing the motor from actuating said tumbler.

4. In a device of the character described, a cabinet, internal walls forming a drying chamber therein at the upper end thereof, and at least

5 10 15 part of an air passageway, a blower arranged in the base of said cabinet and having its inlet communicating with said passageway, said cabinet being provided with an opening for admitting air to said passageway and an air outlet therefrom, a heat exchange device arranged in said passageway and below said drying chamber and having heat generating means associated therewith, said chamber being provided with an inlet communicating with said passageway on the downstream side of said heat exchange device and a vent, a damper adapted to be positioned for closing said inlet or said outlet, a manual control therefor, a motor for driving said blower, a rotary clothes tumbler in said chamber, a driving connection between said motor and said tumbler, and means operated by said manual control for breaking said connection when said chamber inlet is closed.

5. In a device of the character described, a cabinet having a chamber and an air passageway therein, the wall of the cabinet having an air inlet for the admission of outside air into one end of said air passageway, an air blower having its inlet communicating with said passageway, a rotary drier located within said chamber, a power driving means constructed and arranged for simultaneously driving said blower and drier, a heating device arranged in the path of air discharged by said blower during the operation thereof, said chamber having an inlet connected with the discharge side of said blower, said passageway having an outlet for discharging heated air externally of said cabinet, a damper operable for selectively controlling the passage of air into said chamber through the inlet thereof or through said outlet, and common control means operatively associated with said power driving means and said damper operable for shifting said damper to close said chamber inlet and simultaneously therewith effecting the discontinuance of the driving of said rotary drier by said power driving means without discontinuing the driving of said blower thereby, said chamber being provided with an air outlet therefrom.

45
EARL B. HOUGH.
